UNITED STATES PATENT OFFICE.

JOSEPH BECKWITH, OF BROKEN BOW, NEBRASKA.

OIL-BURNER.

1,155,873.

Specification of Letters Patent.

Patented Oct. 5, 1915.

Application filed June 15, 1915. Serial No. 34,201.

To all whom it may concern:

Be it known that I, JOSEPH BECKWITH, a citizen of the United States, residing at Broken Bow, in the county of Custer and 5 State of Nebraska, have invented a new and useful Oil-Burner; and I do hereby declare the following to be a full, clear, and exact description of the invention, such as will enable others skilled in the art to which it 10 appertains to make and use the same.

This invention relates to an oil burner, and an object of the invention is to provide a pair of burner tubes including an intermediate inlet burner tube, which connects 15 the transverse end couplers of the pair of burner tubes, in combination with an improved generator having its outlet end interposed between two sections of the intermediate inlet tube, and through which burner 20 the fuel passes, which fuel or oil is under pressure, and as it enters the sections of the intermediate inlet tube, it mixes with and draws air into the intermediate tube. In other words, the fuel or oil siphons into the 25 intermediate tube, and by virtue of the refractory members the oil stream is broken or divided quickly, so that the oil is readily vaporized by the heat of the burner.

Another object of the invention is to provide 30 a generator consisting of a tube comprising a plurality of coils, through which the fuel passes.

In practical fields the details of construction 35 may necessitate alterations, falling within the scope of what is claimed.

The invention comprises further features and combination of parts, as hereinafter set forth, shown in the drawings and claimed.

In the drawings:—Figure 1 is a vertical 40 sectional view through a portion of the stove, showing the improved oil burner as applied, illustrating the same connected to a suitable tank of kerosene oil under pressure. Fig. 2 is a plan view, showing parts 45 broken away, and parts in section. Fig. 3 is a sectional view on line 3—3 of Fig. 2.

Referring to the drawings, 1 designates a conventional form of stove or range having a fire box 2, in which the oil burner is arranged. The oil burner comprises three 50 burner tubes, two outside burner tubes 4 and 5, and the intermediate burner tubes 6, all of which are arranged in parallelism substantially. The outside burner tubes have 55 their ends threaded as shown at 7, and connecting the threaded ends are the transverse

coupler tubes 8 and 9. The intermediate inlet tube 6 consists of two sections 10 and 11, disposed axially, and have their adjacent cap members 12 and 13 (which are provided with adjacent reduced short extensions 14 and 15) spaced apart, as shown clearly in Figs. 2 and 3, so that the openings 16 of the outlet end 17 of the generator 18 may assume a position between the reduced extensions 14 and 15 and alined therewith. By this arrangement the fuel or oil from the generator emanates from the openings in opposite directions and siphons with the air through said reduced extensions. The oil stream as 70 it enters said sections 10 and 11, through the reduced extensions is divided or broken quickly by the perforated refractory members 19 and 20. The section 10 of the intermediate inlet tube is provided with perforations 21, and has one of its ends connected to the coupler tube 9, by means of the nipple 22. The other section 11 of the intermediate inlet tube is connected to the transverse coupler tube 8 by the nipple 23. The burner 80 tubes 4 and 5 are provided with perforations 24 and 25, and arranged on the interior of said tubes 4 and 5, substantially midway of their ends are perforated refractory members 26 and 27. The generator 18 consists of a fine tube 27^a having one end connected to a suitable or conventional form of valve 28, whereas the body portion of the tube 27^a is constructed into a plurality of generator coils 29, through which the fuel or oil passes 90 to reach the outlet end 17. Connected to the valve 28 in any suitable manner, as shown at 30, so that the oil or fuel may be controlled by the valve proper, (not shown) is what may be termed a wire oil tube 31, which in turn is connected to an air pressure kerosene tank 32, as shown at 33, or may be connected to any other suitable source of supply.

The fuel or oil under pressure leaves the generator coils, by way of the openings 16, 100 and is siphoned in conjunction with air through the extensions 14 and 15, then a flame from any suitable source may be held over the perforations of the intermediate tube 6 and adjacent the perforations of the tubes 4 and 5, thereby causing an ignition of the gases. The continuous flow of the fuel or the oil streams from the openings 16, keeps the burner fed, and as before stated, the oil stream or fuel is divided or broken 110 by virtue of the perforated refractory members 19 and 20, so that the oil is readily

vaporized by the heat of the burner and the refractory material of the members 19 and 20. In operation there is enough air entering the perforations of the tubes 4, 5 and 6 to mix with the fuel and partly combusting, thereby maintaining the refractory members 19 and 20, and 26 and 27 in a highly heated condition. By this form of burner a sufficient quantity of heat may be 10 generated for any suitable stove or range, for cooking purposes.

After the burner has been lighted, there is enough heat therefrom, to heat the coils of the generator, thereby partially generating the oil into gas, which as it leaves the outlet end 17 of the generator, is siphoned with air through the extensions 14 and 15.

It is to be understood that the refractory members 19 and 20, 26 and 27 may be dispensed with, in which case the oil burner 20 will operate equally as well.

The invention having been set forth, what is claimed as new and useful is:—

1. An oil burner comprising outer parallel 25 perforated burner tubes, transverse coupler tubes connecting the ends of said outer perforated tubes, an intermediate inlet perforated tube consisting of two sections, one section being connected to one coupler tube, 30 and the other to the opposite coupler tube, said sections being alined and having their adjacent ends provided with reduced extensions spaced apart from each other, and a generator coil receiving fuel from any suitably supply and having its outlet end provided with openings alined with said reduced extensions.

2. An oil burner comprising outer parallel

perforated burner tubes, transverse coupler tubes connecting the ends of said outer perforated tubes, an intermediate inlet perforated tube consisting of two sections, one section being connected to one coupler tube, 40 and the other to the opposite coupler tube, said sections being alined and having their adjacent ends provided with reduced extensions spaced apart from each other, and a generator coil receiving fuel from any suitable supply and having its outlet end provided with openings alined with said reduced extensions, and refractory members 45 arranged in said tubes.

3. An oil burner comprising outer parallel perforated burner tubes, U-shaped coupler tubes connecting the adjacent ends of 50 said burner tubes, an intermediate sectional inlet perforated tube connecting said coupler tubes, and a generator comprising a tube turned into a plurality of coils arranged immediately above the sectional intermediate perforated tube and between the outer tubes to become heated from the burner tubes, said generator having its outlet end provided with openings, said outlet end being interposed between the adjacent ends of the sections of the intermediate tube with the openings alined with 55 said sections.

In testimony whereof I have signed my name to this specification in the presence of 60 two subscribing witnesses.

JOSEPH BECKWITH.
